FEELER MECHANISM FOR LOOMS

Sherwood O. Dodge, Medford, Mass., assignor to
Guaranteed Parts, Inc., Allston, Mass., a corporation of Massachusetts

Application July 6, 1935, Serial No. 30,075

7 Claims. (Cl. 139—281)

This invention relates to feeler mechanisms for looms and particularly to an anti-friction device for such feeler mechanism as are applied to automatic looms for causing an automatic replenishing mechanism to function when the filling on the bobbin in the shuttle is substantially exhausted.

A certain well-known type of feeler mechanism in common use is provided with a floating side slipping feeler member mounted for bodily movement toward and from the front of the loom and also in a direction longitudinally of a shuttle and the bobbin therein on a support between complementary base and cover portions thereof. The feeler member projects from within its support outwardly through an opening provided therefor between the base and cover and has intermittent sliding contact with both of these members, thereby causing surfaces thereof to wear away at the top, bottom and side of the opening where the feeler is normally located. Considerable wear also takes place upon the feeler member and finally excessive wear upon all of the parts mentioned makes it necessary to replace the injured parts.

The primary object of this invention is to provide an anti-friction device which may be attached to feeler mechanisms of the before-mentioned type for the purpose of eliminating the friction and consequent wear upon the feeler member and also upon the base and cover between which said feeler member slides.

Another object of the invention is to provide an anti-friction device of the character mentioned which may also be utilized as a means for guiding the feeler member and centering the same vertically with respect to the bobbin in the shuttle, thereby preventing injury to the filling upon said bobbin caused by an improper engagement of the filling by the feeler member.

Still another object of the invention is to provide a mechanism which may be adjusted to vary the set or normal position of the feeler member with respect to the longitudinal axis of the bobbin in order that the proper side slipping action of the feeler will be insured as may be determined by the character of the filling employed, the construction of the feeler itself and the position of the bobbin in the shuttle.

The invention consists in a feeler mechanism for looms as set forth in the following specification and particularly as pointed out in the claims thereof.

Referring to the drawing:

Fig. 1 is a plan view of a feeler mechanism

embodying my invention, the feeler being illustrated in feeling position in contact with the filling on a bobbin.

Fig. 2 is a plan view of a portion of the feeler mechanism, the cover for the base of the feeler stand being removed to expose portions of the device which would otherwise be obscured, and the guide roller being illustrated in section.

Fig. 3 is a side elevation of the device as viewed from the right of Fig. 1, the bobbin being illustrated in transverse section.

Fig. 4 is an end elevation of the device as viewed from the right of Fig. 3, the feeler member being illustrated in transverse section in contact with the guide roll.

Like numerals refer to like parts throughout the several views of the drawing.

In the drawing, 5 represents the base and 6 the cover of a feeler stand or support, said cover being secured to the base by means of a screw 7 and the base being secured by means of a bolt or screw 8 to a bracket 9 which in turn is secured to the frame of a loom in a well-known manner. Mounted in the feeler stand between the base 5 and cover 6 thereof is a feeler member 10, said member being mounted for movement toward and from the front of the loom and also in a direction longitudinally of the shuttle and the bobbin therein.

The feeler member 10 has a laterally extending arm 11 embodied therein, the end portion 12 of which is adapted to engage a stop 13 when the feeler is in its rearward or feeling position as illustrated in Fig. 2. A spring 14 is connected to the arm 11 at 15 and to a projection 16 provided at the rear of the base 5, and said spring acts in a rearward direction to move said feeler rearwardly to its feeling position. The feeler member 10 projects from within the feeler stand outwardly through a slot 17 provided between the base and cover portions thereof, and said slot is of sufficient lateral dimension to permit the necessary side slipping action of said feeler when the filling upon a bobbin in a shuttle becomes substantially exhausted and the outer extremity of said feeler engages the bare surface of said bobbin. In Figs. 1 and 2 of the drawing portions of a bobbin or filling carrier A are illustrated and the outer extremity of the feeler 10 is in engagement with filling B located thereon. That portion of the outer extremity of the feeler 10 which engages the filling B and bobbin A is provided with a series of teeth 18. The feeler 10 engages the extremity of a transmitter rod 19 which is operatively connected to and adapted to cause

the actuation of an automatic replenishing mechanism of well-known type whereby replenishment of the filling is effected.

All of the mechanism hereinbefore mentioned including the shuttle, which is not illustrated in the drawing, is old and well known in the art and it is common knowledge that the engagement of the feeler member 10 with the surface of the base 5 and cover 6 causes excessive wear to the feeler and to the base and cover at one side of the slot 17, making it necessary to replace these members frequently. The novelty of the present invention resides in providing a means whereby the feeler 10 may be guided during its forward and rearward movements in a manner to reduce this wear upon the base, cover and feeler, and is as follows:—

Mounted upon the top of the cover 6 of the feeler stand is a bracket 20, and the screw 7, which is provided for the purpose of securing the cover 6 to the base 5 is utilized as a means for securing the bracket 20 to the cover, said screw extending through a slot 21 provided therefor in said cover. As a means furthermore of positioning the bracket 20 upon the cover 6 the bracket is provided with downwardly extending ears 22 which are adapted to engage the sides of said cover and preferably a slight amount of clearance is provided between the adjacent surfaces of said ears and cover for purposes herein-after to be more fully explained.

Secured to the under side of a portion 23 of the bracket 20 by means of a stud 24 and nut 25 is a roller 26 having a groove 27 formed in the periphery thereof. The groove 27 is positioned in vertical alignment with the slot 17 to receive the feeler 10, and said feeler is normally held in frictional contact with the surface of said groove 27 by means of the spring 14. During the operation of the feeler mechanism, as the feeler member 10 thereof is moved forwardly and rearwardly on detecting beats with a working supply of filling B on the bobbin A, the roller 26 constitutes a guide for the feeler and positions the same vertically with respect to the longitudinal median line of the bobbin A, and as the roller is located between the slot 17 and the outer extremity of the feeler 10 the wear which usually occurs upon the surface of the base 5 and cover 6 at the slot 17 by reason of the sliding engagement of the feeler therewith is greatly reduced as is also the wear upon the feeler member itself. The feeler 10 in contacting with the surface of the groove 27 causes the roller 26 to rotate freely upon the stud 24 and the wear caused by frictional contact between these members is therefore negligible.

If it becomes necessary to vary the set or normal position of the feeler member 10 longitudinally of the axis of the bobbin A the same may be accomplished by loosening the screw 7 which secures the bracket 20 to the cover 6 and moving said bracket upon said cover in a manner to move the roller 26 laterally of the feeler. The slot 21 and clearance between the adjacent surfaces of the ears 22 and cover 6 makes it possible to obtain any adjustment of the feeler that may be necessary.

I claim:

1. In a feeler mechanism for looms, the combination of a feeler stand, a yieldable side slipping feeler mounted thereon, a bracket adjustably mounted upon said stand, and a roller mounted upon said bracket and having a groove formed in the periphery thereof in which the

feeler is supported and guided as it is moved forwardly and rearwardly on detecting beats.

2. A feeler mechanism for looms comprising, in combination, a feeler stand, a floating side slipping feeler mounted on said stand for movements toward and from the front of the loom and in a direction longitudinally of a bobbin with which it is adapted to contact, a bracket fast to the stand, a roller on said bracket for guiding and supporting said feeler as it is moved forwardly and rearwardly on detecting beats with a working supply of filling on said bobbin, said bracket being adjustable upon the stand to move said roller laterally of the feeler to vary the set of the latter with respect to the filling upon the bobbin, and a spring acting rearwardly on the feeler to move the latter to feeling position.

3. A feeler mechanism for looms comprising, in combination, a feeler stand, a floating side slipping feeler mounted on said stand for movements toward and from the front of the loom and in a direction longitudinally of a bobbin with which it is adapted to contact, a roller mounted upon said stand and positioned between the stand and the outer end of said feeler, said roller having a groove therein adapted to support and guide the feeler as it is moved forwardly and rearwardly on detecting beats with a working supply of filling on said bobbin, and a spring acting rearwardly on the feeler to move the latter to feeling position and into contact with the groove in the roller.

4. A feeler mechanism for looms comprising, in combination, a feeler stand, a floating side slipping feeler mounted on said stand for movements toward and from the front of the loom and in a direction longitudinally of a bobbin with which it is adapted to contact, a bracket adjustably mounted upon said stand, a roller mounted upon said bracket and positioned between the stand and the outer end of the feeler, said roller having a groove formed in the periphery thereof in which the feeler is supported and guided as it is moved forwardly and rearwardly on detecting beats with a working supply of filling on said bobbin, and a spring acting rearwardly on the feeler to move the latter to feeling position and into contact with the roller.

5. An anti-friction guide for the feeler of a feeler mechanism for looms comprising a bracket adapted to be secured to a feeler stand, and a roller mounted upon said bracket and adapted to have rotary guiding contact with said feeler as the latter is moved forwardly and rearwardly on detecting beats.

6. An anti-friction guide for the feeler of a feeler mechanism for looms comprising a bracket adapted to be secured to a feeler stand, and a roller mounted upon said bracket and having a groove formed in the periphery thereof in which said feeler may be supported and guided as it is moved forwardly and rearwardly on detecting beats.

7. An anti-friction guide for the feeler of a feeler mechanism for looms comprising a bracket adapted to be secured to a feeler stand and a roller mounted upon said bracket and having a groove formed in the periphery thereof in which said feeler may be supported and guided as it is moved forwardly and rearwardly on detecting beats, said bracket being slidable in a horizontal plane upon said stand to move said roller laterally of the feeler to vary the set of the latter with respect to the filling upon the bobbin.
